UNITED STATES PATENT OFFICE.

JESSE T. REZNOR, OF MERCER, PENNSYLVANIA.

GAS-HEATER.

1,163,458.

Specification of Letters Patent.

Patented Dec. 7, 1915.

Application filed June 27, 1914. Serial No. 847,651.

To all whom it may concern:

Be it known that I, JESSE T. REZNOR, a citizen of the United States, and a resident of Mercer, in the county of Mercer and State 5 of Pennsylvania, have invented a new and Improved Gas-Heater, of which the following is a full, clear, and exact description.

My present invention relates particularly to gas heaters of the reflector type, and an 10 object of the invention is to provide means whereby proper combustion of the gas will be maintained and interference with the flame by air currents and eddies will be prevented.

15 A further object of the invention is to provide a heater which overcomes the danger of setting fire to one's clothing by flames issuing from the heater at the front, or by the clothing being drawn into contact with 20 the flame by air currents.

The invention also has for its object to improve heaters of the general character referred to as regards simplicity of construction, and convenience in assembling and re- 25 pairing the parts.

With gas heaters of the reflector type, and in which a burner is disposed at the back of the heater above the reflector, the jets of the burner being disposed forwardly, full gas 30 pressure not infrequently results in the flame issuing beyond the front of the heater. I provide in the present instance a burner at the front of the heater with the jets disposed in a rearward direction, and thereby 35 overcome the danger of the flames issuing beyond the front of the heater. In connection with the burner, also, I provide for maintaining a supply of air to properly sustain combustion, and I provide means for 40 preventing the air currents, counter-currents and eddies from interfering with the flame, and incidentally preventing the clothing of a person standing near the heater from being drawn into the flame, as well as 45 preventing children from reaching the flame and being burned.

The invention will be more particularly explained in the specific description following.

50 Reference is to be had to the accompanying drawings forming a part of this specification, in which similar characters of reference indicate corresponding parts in all the views.

55 Figure 1 is a perspective view of a gas

heater embodying my invention; Fig. 2 is a transverse vertical section on an enlarged scale; Fig. 3 is a detail horizontal section on the line 3—3 of Fig. 2; Fig. 4 is a fragmentary view of a device for establishing 60 connection between the burner and the gas supply, and to be hereinafter more particularly referred to; and Figs. 5, 6 and 7 are fragmentary views in transverse vertical section showing modified arrangements of 65 the air chamber provided in connection with the burner.

Referring more particularly to Figs. 1 to 4, the body 10 of the heater is generally of rectangular form having a front opening 11, 70 in the rear of which is the reflector 12. The body 10 above the front opening 11 constitutes what may be termed a flame chamber, at the front of which is a horizontally disposed burner tube 14, having a longitudinal 75 series of nipples or tips 15, provided with jet orifices disposed toward the interior of the heater.

Above the burner at the top of the flame chamber 13 is a flame plate or baffle plate 16, 80 which is secured to the front 10^a of the body and extends rearwardly therefrom at a slight inclination in the direction of the back of the heater, terminating short of said back. A second baffle plate 17 is disposed 85 reversely to the baffle plate 16, being secured to the back of the heater and extending forwardly a short distance beyond the inner end of the baffle plate 16. The baffle plate 16 is preferably provided with side flanges 16^a, 90 which are secured to the sides of the body 10 by bolts 16^b or their equivalents, there being similar flanges 17^a on the baffle plate 17 secured to the sides of the body 10 by bolts 17^b, or the like. The arrangement of the 95 baffle plates provides an indirect upward flow of the mingled heated air and products of combustion. The air escapes through outlet holes 18 at the top of the body 10, and in some cases the heater body will be 100 provided with a flue connection 19 at the back, in which event much of the products of combustion will pass through the flue.

In order to produce a steady flame and improved combustion, I provide an air chamber 20 in front of the burner tube 14. In the form shown in Figs. 1 to 3, the said air chamber 20 is formed by a vertically curved plate 21 secured at its upper and lower ends in any suitable manner to the 110

front of the body, and forming part of said front. Near the lower end of the plate 21, holes 21' are formed for inlet of air, so that the air will pass through said holes and upwardly through the air chamber 20 over the burner pipe 14, and rearwardly between the said burner tube and the baffle or flame plate 16. Air entering the open front 11 will also pass upwardly to the flame chamber 13, to mingle with the air from chamber 20, above and in the rear of the burner.

I have found that air entering the heater in front of the reflector and rising in the heater, results in currents and eddies that tend to check combustion and curl the flame backwardly, and in order to overcome this I provide a screen 22 disposed horizontally, or approximately so in the heater between the reflector and the burner adjacent to the top of the front opening 11. The screen is formed of wire mesh which does not seriously interfere with the reflection of the flame, and it so modifies the air currents and eddies that the air rises through the screen without disturbing the flame or interfering with combustion, but on the contrary the air passing upwardly, co-acts with the air passing from the chamber 20 beneath the flame plate 16. The result is, that excellent combustion and a steady flame are produced. Furthermore, the screen prevents clothing or the like from being drawn into the flame, and children are barred from reaching the flame, so that absolute safety is attained, with high efficiency.

The chamber 20 is closed at the front below the burner tube 14, by a partition plate 14^a, which extends from the underside of the burner tube to the bottom of chamber 20. The partition 14^a thus prevents the current of air which enters through the open front 11, from passing forwardly to the chamber 20 and prevents any air from the chamber 20 being drawn upwardly and rearwardly in front of the burner from below the latter. The result is that the air currents are prevented from causing a fluttering of the flame, so that the flame will burn steadily and produce a good combustion. Moreover, the current of air passing over the burner tube and beneath the shield plate 16, prevents direct contact of the flame with the said plate; also the air in the chamber 20 will be heated in passing over the burner tube to further aid combustion.

To secure the burner tube 14 and afford access to the same at one end, a plate 23 is provided, closing an opening in the adjacent side of the body 10, and a plate 24 is provided, closing an opening in the heater body at the side adjacent to the opposite end of the burner tube 14. The last mentioned end of the burner tube is closed by a cap nut 25 outside of the plate 24. Said plate 24 may be secured by a bolt 26, and bolts or screws 27

may be employed to secure the plate 23. In the plate 23 I have shown a lighting hole 28 for the entrance of a lighted match.

The gas connection with the burner tube 14 is effected in the following manner: A fitting 29 is adapted to receive a gas tube (not shown) in the usual manner, and is provided with a cock 30, as is usual. The fitting 29 is further provided with a branch or nipple 31 which leads to an elongated box 32 in the interior of the body, and to said box 32 the burner tube 14 is secured at the opposite side of said box from the entrance of the nipple 31. The box 32 is provided with ears 32^a at the sides to receive any suitable fastening devices, such as bolts or screws.

In Fig. 5 an air chamber of modified construction is shown in connection with the burner tube 14. The said air chamber 20 is formed by a continuation 21^a of the front 10^a of the heater body, and the lower end of said extension 21^a is continued inwardly and provided with air inlet holes 21^b below the tube 14, so that air will pass over the burner tube and beneath the flame plate 16^a in the manner previously described, to mingle with the air received in the flame chamber 13 through the described screen 22.

A further slight modification is illustrated in Fig. 6, in which the extension 21^c of the front 10^c corresponding with the extension 21^a is deflected outwardly, instead of being vertical as in Fig. 5. Air is supplied to the flame chamber 20^c formed by the said extension 21^c through the inlet holes 21^c formed in the inwardly projecting lower end of said extension 21^c, and will pass upwardly above the burner tube, beneath the baffle plate 16^b.

In the form shown in Fig. 7, an extension 21^e is given the form of three sides of a rectangular box in front of the burner tube 14, thereby forming an air chamber 20^e having air inlet holes 21^e so that air will pass upwardly over the burner tube beneath the baffle plate 16^c.

Having thus described my invention, I claim as new and desire to secure by Letters Patent:

1. A heater of the character described, comprising a hollow body open at the front near the bottom for the free inlet of air, a baffle plate extending from the front of the body rearwardly and terminating short of the back, forming a flame chamber, a burner tube in said flame chamber, near the front of the heater below the baffle plate and above the front opening in the body, and an air chamber at the front of said burner, the said air chamber having an inlet independently of the mentioned front opening in the body and discharging air above the burner, between the same and the baffle plate.

2. In a heater of the character described,

5 a hollow body having a front open at the lower portion for the free inlet of air, a flame chamber in the heater above the said opening, a screen between the flame chamber and the open lower portion of the heater, and a burner in the flame chamber above the screen.

10 3. In a gas heater of the character described, having a front opening at the lower portion, a burner disposed at the front of the heater and having rearwardly disposed jet openings, and a screen adjacent to the top of the front opening and below the said burner.

15 4. In a gas heater of the character described, a heater having a front opening at the lower portion for the free inlet of air,

a burner within the heater, at the front of the latter, and arranged to produce a rearwardly disposed flame, a flame plate above 20 the said burner extending from the front of the heater rearwardly, means for supplying air from the front of the heater between the burner and flame plate, and a screen below the burner and adjacent to the top of the 25 front opening.

In testimony whereof I have signed my name to this specification in the presence of two subscribing witnesses.

JESSE T. REZNOR.
